COMBINED CARD READER AND CARD PUNCH MACHINE OR SIMILAR ARTICLE

John David Jagger, Morgan Hill, Calif., assignor to International Business Machines Corporation, New York, N.Y., a corporation of New York

Filed Aug. 23, 1962, Ser. No. 71,431

Term of patent 14 years

(Cl. D26—5)

FIG. 1

FIG. 2

FIG. 3

FIG. 1 is a front perspective view of a combined card reader and card punch machine or similar article according to the present invention;

FIG. 2 is a rear perspective view thereof; and

FIG. 3 is a top view thereof.

The dominant features of my new design are shown in solid lines in the drawing.

I claim:

The ornamental design for a combined card reader and card punch machine or similar article, as shown and described.
